UNITED STATES PATENT OFFICE.

MATHEW B. MORGAN, OF CLEVELAND HEIGHTS, OHIO, ASSIGNOR TO CLEVELAND TRACTOR COMPANY, OF CLEVELAND, OHIO, A CORPORATION OF OHIO.

PILOT ATTACHMENT FOR TRACTORS.

1,369,696.

Specification of Letters Patent. Patented Feb. 22, 1921.

Application filed June 27, 1919. Serial No. 307,123.

To all whom it may concern:

Be it known that I, MATHEW B. MORGAN, a citizen of the United States, residing at Cleveland Heights, in the county 5 of Cuyahoga and State of Ohio, have invented a certain new and useful Improvement in Pilot Attachments for Tractors, of which the following is a full, clear, and exact description.

10 This invention relates to pilot wheel attachments for tractors. The objects of the invention are, first, to provide, for the raising and lowering of the pilot wheel, means which may be easily rendered inoperative 15 and put in an out-of-the-way position, or which may be instantly rendered operative, as desired. Second, to provide means for easily and quickly connecting the pilot attachment to and disconnecting it from the 20 tractor.

The invention consists in the construction and combination of parts shown in the drawings and hereinafter described and pointed out definitely in the appended 25 claims.

In the drawings, Figure 1 is a plan view of the invention, said view showing, in a fragmentary way, only so much of the tractor as is necessary for the disclosure of the 30 invention; Fig. 2 is a side elevation of the parts shown in Fig. 1; Fig. 3 is an enlarged plan view of the means through which the operating lever may be connected with the pilot wheel frame; Fig. 4 is an 35 enlarged side elevation of said mechanism; and Fig. 5 is a vertical section in the plane of line 5—5 on Fig. 1; and Fig. 6 is a plan view of a part of rock shaft 21 and one of the split bearing sleeves thereon.

40 In the drawing, 10 represents the main frame of the tractor. The driver's seat 12 is carried by this main frame near the rear end thereof.

The pilot wheel attachment includes the 45 transversely extended rock shaft 21 mounted in suitable bearing brackets 12, secured to the front end of the tractor main frame 10 as will be presently described. This pilot attachment also includes a rigid frame 50 which may comprise in addition to the rock shaft, two members 22, 23. These extend forward and toward the right from opposite ends of the rock shaft 21. In the front end of this pilot frame, which lies well to

the right of the main frame, the pilot wheel 55 24 is mounted.

25 represents the operating lever which, at its front end, loosely embraces the rock shaft 21, and extends from the rock shaft 60 rearward to a position where its rear end will be within more or less easy reach of the driver, whose seat 50 is secured to the rear end of the main frame. When the pilot attachment is in use, performing the functions for which it is provided, the rock 65 shaft 21 may rock, as it will because of the unevenness of the furrow in which the pilot wheel is running, but without causing any movement of this operating lever. This is because under the conditions stated, there 70 is no operative connection between the lever and rock shaft; and the rear end of said lever rests upon a bracket 26. A hook catch 27 is pivoted to an adjacent bracket 28,—both of said brackets being connected with 75 the main frame of the tractor. The position of the bracket 28 is such that the hook 27 may engage a part of the rear end of the lever 25. The lever is bent into substantially the form shown, its front end being a substantially vertical arm 25^a.

A hook-shaped arm 30 is fixed to rock shaft 21, and extends upward and forward therefrom. A bell crank lever is pivoted to the substantially vertical front end 25^a of 85 the lever 25. One arm 31 of this bell crank has a horizontal transverse end 31^a for engagement with the arm 30. To the other arm 32 of the bell crank the rod 33 is connected. This extends rearward in guide- 90 ways 25^b carried by the lever 25 to a position where it may be conveniently taken hold of and moved endwise by the driver of the tractor.

When the driver wishes to raise the pilot 95 wheel above the ground he swings the rear end of said lever upward, the lever turning on the rock shaft 21. As the lever so turns, the end 31^a of the bell crank will first engage the top of arm 30,—will then slide 100 along on said top, and will finally drop down in front of arm 30, there being a spring 35 to cause said bell crank arm to swing in the manner stated.

An operative connection has now been 105 made between the lever and the arm 30 attached to the rock shaft. The operator may now move the rear end of the lever 25

downward with the result of lifting the pilot wheel frame so as to raise the pilot wheel above the ground. The rear end of said lever 25 may now be engaged and held 5 down by the hook 27. When the pilot frame is to be lowered again into operative position, the driver brings about this result by the reverse movement of the lever 25. When the pilot wheel is resting in the furrow, the 10 driver by pulling rearward on the rod 33 will swing the bell crank arm 31 out of engagement with the arm 30, thereby again disconnecting the pilot frame and its operating lever. The lever may then be restored to the inoperative and out-of-the-way position described.

In order to facilitate the connection of this pilot frame with the tractor in the desired relation thereto, and to likewise prevent any lateral movement of the pilot frame after it has been so connected, two split bearing sleeves 40 are clamped around the rock shaft 21 at suitable places. Each of these sleeves has an externally cylindrical 25 portion 41 which lies between two outwardly extended flanges 42. Brackets 12 are fixed to and project forward from the front end of the tractor frame. Each bracket has at its front end one half 15 of a cylindrical 30 bearing box adapted to fit around the cylindrical part of the sleeve 40 and between the flanges thereof. The other half or cap 16 of this bearing is secured to the part 15 by means of a U-bolt 45 which externally 35 braces the cap and which passes through flanges 17 along the sides of the part 15. To connect and disconnect this entire pilot attachment with the tractor the operator has merely to screw on or unscrew the four 40 nuts which engage the threaded ends of the U-bolts.

Having described my invention, I claim:

1. The combination with a tractor, and a pilot wheel attachment connected therewith, 45 said connections including a transversely extended rock shaft, which is a part of the attachment, and bearings which are connected with the tractor frame and in which said rock shaft is mounted for rocking movement, with an operating lever loosely mounted 50 on said rock shaft and extending rearwardly therefrom, and means controllable

from the rear end of the tractor for operatively connecting the rock shaft and lever.

2. The combination with a tractor, a pilot 55 wheel attachment connected therewith, said connections including a transversely extended rock shaft, which is a part of the attachment, and bearings which are connected with the tractor frame and in which said rock shaft is mounted for rocking movement, with an operating lever loosely mounted on said rock shaft and extending rearwardly therefrom, an arm fixed to said rock shaft, a lever pivoted to said operating lever for 60 engagement with said arm, and means operable from the rear end of said lever for controlling said lever to permit or prevent its engagement with said arm.

3. The combination of a tractor, and a 70 pilot attachment pivotally connected therewith, with an operating lever fulcrumed on said attachment, and means controllable from said tractor for operatively connecting and disconnecting the lever and the attachment.

4. The combination of a tractor, and a pilot attachment pivotally connected therewith, with an operating lever fulcrumed on said attachment, mechanism operatively 80 connecting and disconnecting the lever and the attachment, and means carried by said lever to control said mechanism.

5. The combination of a tractor, and a pilot attachment pivotally connected therewith, with an operating lever fulcrumed on said attachment, mechanism for operatively connecting the lever with the attachment to raise and lower said attachment and for disconnecting it to permit the operating end 90 of said lever to be swung out of the way when not in use, and means adapted to secure said lever when swung out of the way.

6. The combination of a tractor, having a 95 driver's seat near its rear end, a pilot attachment pivotally connecting with the front end of the tractor, an operating lever for elevating said pilot attachment, and means operable from the driver's seat for connecting and disconnecting the pilot attachment 100 and its operating lever.

In testimony whereof I hereunto affix my signature.

MATHEW B. MORGAN.
